INVENTOR
Jan Krzesinski
BY George C. Hinckley
ATTORNEY

UNITED STATES PATENT OFFICE.

JAN KRZESINSKI, OF NANTICOKE, PENNSYLVANIA.

PADLOCK.

Application filed December 1, 1922. Serial No. 604,232.

To all whom it may concern:

Be it known that I, JAN KRZESINSKI, a citizen of Poland, residing at Nanticoke, county of Luzerne, and State of Pennsylvania, have invented certain new and useful Improvements in Padlocks, of which the following is a specification.

This invention relates to keyless padlocks, and it is the principal object of the invention to provide such a padlock with an acoustic warning signal giving an alarm if any person not known the secret of opening the lock should try to open it with a key.

These and other objects of my invention will become more fully apparent as the description thereof proceeds, and will then be more specifically pointed out in the accompanying drawing in which:

Figure 1 is an interior view of the padlock after the removal of its rear wall, looking in the direction of line 1—1, Figure 2.

Figure 2 is a vertical section through the same on line 2—2 of Figure 1.

Figure 3 is a horizontal section on line 3—3 of Figure 4.

Figure 4 is a detail view on an enlarged scale of the upper part of the pad lock, the view being taken along line 4—4 of Figure 3.

Figure 5 is an end view of the lock.

The lock comprises a casing 10 closed by a front wall 11 and rear wall 12, connected by a band or end wall 13 in the usual manner to form the casing.

The front and rear walls 11 and 12 carry suitable eyes 14 and 15 in which the ends of a pin 16 rest, to which one end of the shackle 17 is pivotally secured, the other, 40 extended end of which enters the casing through a slot 18 in the upper part of its end wall 13. A horizontal bar 19 is slid- 45 ingly guided through the upper part of the casing above a stationary partition 20 with- in the same, and its ends extend out of the casing. A pin 21' on bar 19 within the cas- 50 ing near one end thereof limits the move- ments of said bar and prevents a complete withdrawal of the opposite end of the bar into the casing.

The rod or bar 19 is provided at its upper edge with a recess 21, and in its side wall with a vertical recess or depression 22 ending into an elongated part 23 forming a 55 tongue 24 on the side face of bar 19 adapt- ed to be engaged by a recess 24' in the side

face of the extended end of shackle 17. A vertical plate 25 is secured with its upper end to the front edge of band or end wall 13 and at its lower end to partition 20, and is provided with a square opening 26 allowing the passage of a transversal pin 27 ex- 60 tends through the rear wall 12 and the front wall 11, and this pin carries at its front end outside of the casing 10, a knob 28. Intermediate its ends the pin 27 has a recess 29 adapted to engage the upper edge 65 of bar 19.

A frame 30 secured to the inner face of front wall 11, carries a bell 31, the striker 32 for which is arranged at the upper end of a curved pin 33, the lower end of which is secured to a stub shaft 34 journaled in the frame 30.

This shaft also carries a double pawl 35 secured intermediate its ends to said shaft and adapted to engage with its hooked ends 36 and 37 the teeth of a ratchet wheel 38 on a shaft 39 journaled in frame 30.

Upon this shaft, laterally disposed to ratchet 38, is secured a pinion 40, the teeth of which are in engagement with the teeth 41 on the outer periphery of a drum 41' on shaft 42 containing a watch spring 43 hav- 75 ing one of its ends secured to shaft 42 and its other end secured to the inner wall of said drum. The front wall 11 of the casing has a key hole 44 in which an elastic angular finger 45 is secured, the lower end of one arm of which is attached to a stub shaft 46, 80 while the upper end 47 of its other arm, which is wedge shaped, engages a lever 48 if a key is inserted into key hole 44 and presses lever 48 down to disengage the hook shaped ends of pawl 35 from ratchet 38.

The outer end of drum shaft 42 is extended through rear plate 12 and carries a winding key 49.

The lock operates as follows:

If any person not acquainted with the mechanism attempts to open the lock by means of a key introduced through key hole 44, he will press finger 45 towards the inside which will compel its wedge face to depress bar 48 and release the pawl 35 allowing the spring to operate the striker and an acoustic alarm will be given deterring the person from further attempts to open the lock.

Having thus described my invention what I claim as new and desire to secure by Let- 110 ters Patent is—

1. A keyless pad lock having key oper-

ated means and an alarm operated by said key operated means, the key operated means being without effect on the locking means of the pad lock.

5. 2. A pad lock including a casing formed with a key hole, means to be actuated by a key introduced through said key hole, an alarm mechanism operated by said means,

and means for operating the lock wholly independent of the key operated means and ¹⁰ arranged beyond possible actuation by said key operated means.

In testimony whereof I have affixed my signature.

JAN KRZESINSKI.
